Primary Examiner—Catherine Tuttle(74) *Attorney, Agent, or Firm*—Gerald E. Helget; Nelson R. Capes; Briggs and Morgan, P.A.(57) **CLAIM**

The ornamental design for a novelty noisemaker incorporating inflated stick with stiffened flag, as shown and described.

DESCRIPTION

FIG. 1 is a front elevational view showing my new design for a novelty noisemaker incorporating inflated stick with stiffened flag, which is a mirror image of the rear elevational view;

FIG. 2 is a right side elevational view;

FIG. 3 is a left side elevational view;

FIG. 4 is a bottom plan view; and,

FIG. 5 is a top plan view.
